UNITED STATES PATENT OFFICE.

ALVA J. FISHER, OF EVANSTON, ILLINOIS, ASSIGNOR TO HURLEY MACHINE COMPANY,
OF CHICAGO, ILLINOIS, A CORPORATION OF ILLINOIS.

AGITATING MECHANISM.

1,184,087.

Specification of Letters Patent.

Patented May 23, 1916.

Application filed August 22, 1911. Serial No. 645,423.

To all whom it may concern:

Be it known that I, ALVA J. FISHER, a citizen of the United States, residing at Evanston, Cook county, Illinois, have invented certain new and useful Improvements in Agitating Mechanism, of which the following is a specification.

My invention relates to agitating mechanism that may have a variety of applications or uses such as for washing machines, churning, ice cream freezers, and so forth.

The object of my invention is to provide novel, efficient and reliable mechanism of this character and one moreover which is compact and economical of manufacture.

By my novel mechanism the rotary motion from any source of power such as an electric motor or gasoline engine is transformed into the desired oscillating motion for agitating purposes.

Other novel and advantageous features of construction and operation will be apparent from the description hereinafter given.

In the drawings Figure 1 is a sectional elevation of my device or mechanism illustrated in connection with one specific use or application such as a washing machine, a portion of which is shown; Fig. 2 another side elevation of such mechanism; Fig. 3 a sectional plan view on the line 3-3 of Fig. 1; Fig. 4 a section on the line 4-4 of Fig. 2 and Fig. 5 an elevation of the parts illustrated in Fig. 4.

While as hereinbefore stated my invention may have a variety of applications or uses, yet for the purpose of a clear disclosure of my invention I have chosen to illustrate such invention in connection with a washing machine, a portion of which is illustrated in the drawings, but it will be understood that I do not limit myself in this application to this specific use.

As herein shown the agitating mechanism is mounted upon a frame or base plate 1 which in turn, in the specific instance being described, is secured in suitable manner to the legs 2 of a washing machine 3. Upon this frame or plate in the bearing 4^a is mounted a main shaft 4 to which is secured a pulley 5 driven by means of the belt 6 from a small pulley 7 on the armature 8 of an electric motor 9 which is herein shown as the prime mover although any other source of power may be utilized. To this shaft is secured a pinion 10 meshing with

a large gear 11 secured to a shaft 12 which is journaled in the bearings 13 on the plate or frame 1. This gear is provided on one side with a crank arm 14 which is pivotally connected by means of a link 15 with a reciprocating rack bar 16. As shown more particularly in Fig. 2 this bar has at one end a depending and offset portion 16^a to whose lower end the outer end of the link 15 is pivotally connected. This bar is adapted to reciprocate or slide in posts or standards 17-18 rising vertically from the base plate or frame and preferably forming an integral part thereof. These standards are slotted to form guideways for the bar and in order to reduce the friction of reciprocation to a minimum such guideways are provided with small anti-friction rollers 19 adapted to bear on the top and bottom respectively of the rack bar as clearly indicated in Figs. 2, 4 and 5, it being understood that only the standard 17 is so equipped with these rollers although if desired the other standard 18 may be similarly equipped. Furthermore these rollers which are mounted upon short pins or shafts 20 which pass through the vertical slots 21 of the standards are adjustable vertically, the same being held in any desired adjusted position by means of the nuts 22.

The bar 16 is provided at its free end with the rack 16^b preferably formed integral therewith with the teeth arranged in a vertical plane and in position to mesh with the pinion 23. This pinion is secured to a vertical shaft or rod 24 which is directly secured to the agitating device of the washing machine in the present instance.

From the foregoing description it will be understood that the rotary movement transmitted from the electric motor is translated into a reciprocating movement of the pinion 23 and its rod or shaft 24, which, it will be understood, may be adapted to any sort of agitating device according to the particular application or use to which my agitating mechanism is applied. This rotary movement is transmitted from the large pulley 5 to its pinion 10 and thence to the large gear 11. This movement is thereupon transmitted through the connecting rod 15 to the rack bar 16 which is caused to reciprocate in the guides or standards 17 and 18. This reciprocating movement of the rack bar is thereupon transmitted from the rack 16^b to

the pinion 23 which is given an oscillating movement. I thus provide an agitating mechanism which is not only simple in construction and economical of manufacture but also compact, efficient and reliable in actual use.

I claim:

1. Agitating mechanism comprising a rotatable driving wheel arranged in a vertical plane and having a crank arm on one side, a reciprocating rack bar arranged at the other side of the wheel and extending in a plane parallel to said wheel with one end adjacent the axis of such wheel, a pinion mounted on a vertical axis and operated by the rack, and a connecting rod arranged in a plane substantially parallel with the planes of said wheel and rack bar and connecting between the crank arm and rack bar, said rod connecting direct with the bar; substantially as described.
2. Agitating mechanism comprising a prime mover 9, a wheel 5 operating thereby, a shaft 4 to which such wheel is secured, a pinion 10 on said shaft, a gear wheel 11 with which such pinion meshes and which is provided with a crank arm 14, a connecting rod 15 having one end connected with said arm and arranged on one side of the gear wheel, a rack bar 16 arranged on the other side of the gear wheel with one end extend-

ing adjacent the axis of such gear wheel, said rack bar extending substantially parallel with a connecting rod and connected to the other end thereof, and a pinion 23 operated by the rack bar, substantially as described.

3. Agitating mechanism comprising a base plate 1 having thereon bearings 4^a and 13 and also standards 17 and 18 having guide-ways, a motor 9 mounted on the base plate, a main shaft 4 journaled in the bearing 4^a, a pulley 5 on said shaft operatively connected with the motor, a pinion 10 on the shaft, a second shaft 12 journaled in the bearing 13, a gear wheel 11 secured to said shaft 12 and having a crank arm 14, said gear wheel meshing with and driven by the pinion 10, a rack bar 16 arranged to slide in the guide ways of the standards and provided with rack teeth 16^b, said bar having an angular extension 16^a, and a connecting rod 15 having a corresponding angular extension and connected at its opposite ends respectively with the crank arm and the extension, said rack bar and connecting rod being disposed on opposite sides of the gear wheel 11.
